[57] CLAIM

The ornamental design for a portable high chair attachment seat, as shown and described.

DESCRIPTION

FIG. 1 is a right elevational view of a portable high chair attachment seat showing our new design;

FIG. 2 is a front elevation thereof;

FIG. 3 is a rear elevation thereof;

FIG. 4 is a top plan view thereof; and

FIG. 5 is a bottom plan view thereof.

The side of the attachment seat not shown is a mirror image of the side shown in FIG. 1.

FIG. 1

FIG. 2

FIG. 3

FIG. 4

FIG. 5
